The ornamental design for a nose cover for eyeglasses, sunglasses, goggles, or like eyewear, as shown and described.

DESCRIPTION

FIG. 1 is a perspective view of a nose cover for eyeglasses, sunglasses, goggles, or like eyewear showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof, the right side elevation view being a mirror image; and,

FIG. 7 is side elevation cross-section view thereof taken along line 7—7 in FIG. 4.

The broken lines immediately adjacent shaded areas represent bounds of the claimed design and environment while all other broken lines are directed to environment and are for illustrative purposes only. The broken lines form no part of the claimed design.
